(57) **CLAIM**

The ornamental design for a thin exit device, as shown and described.

DESCRIPTION

FIG. 1 is a front perspective view of a thin exit device according to our new design.

FIG. 2 is a front view of the thin exit device as in FIG. 1.

FIG. 3 is a top side view of the thin exit device as in FIGS. 1-2.

FIG. 4 is a back view of the thin exit device as in FIGS. 1-3.

FIG. 5 is a bottom side view of the thin exit device as in FIGS. 1-4.

FIG. 6 is a right end view of the thin exit device as in FIGS. 1-5; and,

FIG. 7 is a left end view of the thin exit device as in FIGS. 1-6.
